UNITED STATES PATENT OFFICE.

ALBERT R. SEAMAN, OF CONNELLSVILLE TOWNSHIP, PENNSYLVANIA.

AUTOMATIC FIRE-LIGHTER.

SPECIFICATION forming part of Letters Patent No. 703,841, dated July 1, 1902.

Application filed January 8, 1901. Serial No. 42,507. (No model.)

To all whom it may concern:

Be it known that I, ALBERT R. SEAMAN, a citizen of the United States of America, residing in Connellsville, in the county of Fayette 5 and State of Pennsylvania, have invented a certain new and useful Improvement in Automatic Fire-Lighters; and I do hereby declare that the following is a full, exact, and clear description of the invention, such as will 10 enable others skilled in the art to which it appertains to make and use the same.

My invention relates to improvements in automatic fire-lighters; and the object of my invention is the provision of a simple, inexpensive, and practical device which will at a 15 set and determined time operate automatically to ignite the fire, and thus save time, trouble, and inconvenience usually experienced.

With this object in view my invention consists of an automatic fire-lighter embodying novel features of construction and combination of parts, substantially as disclosed herein.

Figure 1 represents a perspective view of 20 my device set and ready for operation. Fig. 2 represents a similar view taken from the rear; and Fig. 3 represents a detail view of the clock, showing the connection therewith for operating my device.

In the drawings, A designates a base-plate, which also serves as a friction-plate for lighting the match, and upon the base-plate is mounted at B, adjustable by nut-and-bolt connection, the block C, which is provided 25

with a kerf or channel D, in which fits and travels the arm E of the spring-coil F, said coil being mounted in a recess G of the block or body, and the free end of the spring-arm carries a tubular match-holder H, in which 30 is placed a match J, and to retain the arm in position ready for release I provide the pin K, which is seated in an opening in the block. From this construction it will be seen that the block is mounted on the friction base-plate and that the arm carrying the match 35 is retained ready for operation by the pin, and from said pin leads a chain or cord L to the tripping or alarm-operating arbor M of the alarm-clock N, the clock being on a shelf or retained by means of the leg-sockets O and the pivoted retainer O' on the body, and

when the set time for lighting the fire arrives the alarm-arbor turns, drawing the cord or chain and releasing the spring-arm, the cord or connection between the pin and alarm-arbor being so arranged that the turning of the arbor draws the pin out, which carries the match over the friction-plate and brings it lighted in contact with the wick P, carried by the spring-clasp Q, which is secured 55 to the angular metal fender R, which fender is secured upon the board or lever S, which is hinged at T to the body, and a cushion-spring U is provided at the other end of the lever to relieve shock to the parts when the spring-arm contacts with the fender. To prevent loss of the pin, I provide the cord or chain V, which is secured at one end to the said pin and at the other end to the pintle W of the hinge T, as will be apparent. 60

In use the spring-arm with match is retained in position shown in Fig. 1, and when the clock designates the time that the fire is to be lighted the alarm-arbor turns and withdraws the pin, the arm with match lights the 65 match on the friction-plate and applies the match to the wick, which being adjacent to the kindling lights it and starts the fire automatically. 70

It will be seen that my device will light the 80 fire at the determined time and will save the time and prevent the annoyance incident to the person being obliged to get up and perform this labor.

I claim—

1. An automatic fire-lighter, composed of a base-plate, a body adjustably connected thereto, a spring match-carrier mounted in the body, a lever connected to the body and carrying a lighter, and devices for retaining 85 and releasing the match-carrier at the proper time to apply the match to the said lighter.

2. An automatic fire-lighter, composed of a base-plate, a body thereon, a lever hinged to the body, a spring-cushion at one end of 90 said lever, a metal fender at the other end, a lighter secured to the fender, a spring-operated match-carrier in the body, a pin for holding the carrier with match, a clock connected with the pin to release the same at the set 95 time to allow the carrier to apply the match to the lighter. 100

3. An automatic fire-lighter, composed of a base-plate, a body thereon, devices carried by the body for securing the clock, a spring match-carrier in the body, a cushioned lever hinged to the body and carrying a torch or lighter, devices for retaining the match-carrier, and devices connected with the clock mechanism for releasing the pin and allowing the carrier to strike the match and light the lighter or torch.
- 5 A. R. SEAMAN.
